UNITED STATES PATENT OFFICE.

ROBERTO HEYDRICH Y MARTINEZ, OF HABANA, CUBA.

SIPHONIC FLUSHING DEVICE.

Application filed March 14, 1927, Serial No. 175,351, and in Cuba March 1, 1927.

This invention refers to a siphonic flushing device used for the discharging of receptacles, and especially referring to such a device used to operate the discharge of water-closet tanks; and has for its main object the providing of a device adaptable to tanks of this kind, and also to any other kind of tank or receptacle, which device operates pneumatically, and prevents all kind of wear, and also all possibility of obstruction in filling or discharging of the tank or receptacle.

At the same time the use of this device prevents the overflowing of the tank, due to imperfect condition of the inlet cocks or of the floaters, because before this can occur, a complete discharge of the tank will have taken place.

More advantages and other considerations pertaining to this invention will be deduced in the course of this specification, especially by those persons skilled in the art to which this pertains, and with the aid of the figures in the attached drawings, in which the same characters of reference designate the same parts.

In the drawings:

Fig. 1 is a vertical sectional view of a tank provided with a siphonic flushing device according to this invention, showing an operative position.

Fig. 2 is a vertical diametrical section in detail and on enlarged scale, of the device.

Fig. 3 is a horizontal section on lines 3—3 of Fig. 2.

Fig. 4 is a side elevation, partially cut, of the device.

In Fig. 1 is shown a tank 1 such as used in water closets, and in the bottom of which is an opening 1', on which is screwed a branch of the discharge pipe 2 by means of a packing, comprised of a nut 3 and a washer or packing ring 4, placed between an annular flange 2' integral with the pipe 2 and the bottom of the tank 1. In the lower end of the pipe 2 which projects out from the tank is screwed the branch of the discharge pipe which leads to the bowl of the water closet, which is not shown.

At 5 is designated a cylindrical casing open at the top, and which has in its bottom 5' an opening through which passes the upper part of the pipe 2 which projects within the tank 1, and is fastened to the same by a nut 6 screwed to the pipe 2 and

abuts against the flange 2' so that the bottom of said casing 5 is spaced slightly with regards to bottom of the tank 1 (Figures 1 and 2).

Covering the upper part of the pipe 2 is a cover 7 in shape of a bell, resting on the bottom of the casing 5 and leaving with respect to the wall of the same an annular chamber 8. The bell 7 presents in its lower part a plurality of spaced openings 7' to permit the passage of the liquid to the space 9 between the pipe 2 and the bell 7.

Around the receptacle 5 is placed a second bell shaped cover, 10, which has its mouth slightly narrowed and rests upon a peripheral edge 5' which constitutes an integral extension with the bottom of the annular chamber 11. In the lower part of the bell 10 there are a series of spaced openings 12 and from this lower part, over the lines of openings 12 extends a flange 10' which is prolonged lower than the edge 5' for the purpose which will be explained hereinafter and leaving a space or annular chamber 13 with respect to the body of the bell 10.

At the top of the bell 10 is fastened an eye bolt 14, and to it is secured a cable 15 which at its other end is fastened to the lever or arm 16 usual in tanks of this kind, and which is operable by a chain 17, although this last arrangement may be changed, and any other form of connection may be used with the bell 10, so as to be suitable to the kind of tank to which the device is applied.

The working of the device is as explained in the following:

Assuming the parts placed in the position shown in Fig. 2, that is, the bell 10 resting upon the edge 5' of the receptacle 5. The level of the water in the tank is suitably determined by a float or other means at such a point above the bell 10 so that the water which flows through the openings 12 will fill the chamber 11 not higher than the upper edge of the casing 5, the air pressure existing in the space between the bells 7 and 10, preventing the overflow to the chamber 8. The water contained in the space 9 will remain at a level with the upper edge of said pipe 2 and the water contained in the chamber 8 at a much lower level due to air pressure within the bell 10 equal to the head of water in the reservoir.

If the chain 17 is pulled and the bell 10

is raised as shown in Figure 1, then as the space between the bells 7 and 10 becomes greater, the air pressure between the same will be diminished, and the water which is in the chamber 11 will overflow into the tank 8 establishing a siphon draft toward the pipe 2 through the openings 7' and discharging the water through the pipe 2, to the bowl, as shown by the arrows, in Figures 1 and 2.

In the meantime, upon discontinuing the pull on the chain 17, the bell 10 will again rest upon the edge 5' and the discharge will continue, the water which is in the tank 1 flowing through the openings 12, under the flange 10' which extending downwardly below the edge 5' approximately to the bottom of the tank 1, will cause all the water contained in the tank 1 to be discharged through the pipe 2.

When the discharge is completed, there will remain only a small quantity of water in the chambers 9 and 11 the level of which will be different, due to the difference in pressures existing under the bells 7 and 10, as may be seen in Figure 2. The water which continues to flow through the openings 12, coming from the inlet pipe to the tank can only reach a level in the chamber 11 lower than the edge of the receptacle 5, due to the air pressure existing in the chamber 10.

It is evident that within the principles of construction before explained, many changes may be made, without departing from the substantial ideas of this invention, so that I do not limit myself to that which has been described, but wish that the Letters Patent protect that which is consigned within the scope of the following.

Claims:

1. In a siphonic flushing device for the discharging of tanks, a discharge pipe having the end thereof extending into the tank, a receptacle secured around said end, having its bottom above the bottom of the receptacle, a cover in the shape of a bell fixed within the receptacle, covering the end of said discharge pipe and spaced from the same and from the receptacle, having in its lower part a plurality of passages for the liquid, a second cover in the shape of a bell covering the receptacle and spaced from the same and held spaced from the bottom of said receptacle, having a plurality of passages in the lower part for the admission of the liquid, a connection to raise the second bell at will and initiate the discharge of the tank at will, and an imperforate flange covered by said second bell shape cover, extending to a plane below the bottom of said fixed receptacle, when said bell shaped cover is in place.

2. In a siphonic flushing device for the discharging of tanks or receptacles, the ar-

rangement of a discharge pipe, a receptacle secured around the upper part of the end of the discharge pipe which projects within the tank or receptacle, and the bottom of which is slightly separated from the bottom of the tank or receptacle, a cover of bell shape covering the said upper part of the pipe and spaced with relation to same and with the receptacle forming annular chambers with relation to the one and the other body, having in its lower part a plurality of passages which puts in communication the liquid contained in each chamber, a second cover of bell shape covering the receptacle and spaced with same constituting an annular chamber; said second chamber having in its lower part a plurality of passages for the inlet of the liquid contained in the receiving tank to the annular chamber referred to; a peripheral border which extends slightly below the supporting plate which is formed by the receptacle, and mechanism to cause the raising of the second cover at will.

3. A siphonic flushing device for tanks in which liquid may be stored at a predetermined constant level, including a discharge pipe projecting into said tank to a point below said predetermined level, and normally subject to atmospheric pressure, a bell enveloping said pipe forming an annular chamber therearound open to atmosphere by way of its discharge pipe, said bell being open adjacent the bottom to give access of liquid from without said chamber, so as to form a water seal for said chamber, a larger bell submerged below the level in said reservoir enveloping the small bell in spaced relation thereto and open adjacent its lower end to the liquid in said reservoir, said larger bell enclosing in its upper part a body of air under a super-atmospheric pressure equal to the head of liquid in the reservoir, a receptacle open at its top and closed at the bottom arranged between said bells, communicating with the smaller bell adjacent the bottom thereof and extending substantially to the height of the liquid rising in said larger bell against the air pressure therein, said larger bell being movable upwardly with respect to said smaller bell to reduce the air pressure between said bells and initiate the flow of liquid over the top edge of said receptacle.

4. A siphonic flushing device for tanks in which liquid may be stored at a predetermined constant level, including a discharge pipe projecting into said tank to a point below said predetermined level, and normally subject to atmospheric pressure, a bell enveloping said pipe forming an annular chamber therearound open to atmosphere by way of its discharge pipe, said bell being open adjacent the bottom to give access of liquid from without said chamber, so as to

form a water seal for said chamber, a larger bell submerged below the level in said reservoir enveloping the small bell in spaced relation thereto and open adjacent its lower 5 end to the liquid in said reservoir, said larger bell enclosing in its upper part a body of air under a super-atmospheric pressure equal to the head of liquid in the reservoir, a receptacle open at its top and closed at the 10 bottom arranged between said bells, communicating with the smaller bell adjacent the bottom thereof and extending substantially to the height of the liquid rising in said

larger bell against the air pressure therein, said larger bell being movable upwardly 15 with respect to said smaller bell to reduce the air pressure between said bells and initiate the flow of liquid over the top edge of said receptacle, said larger bell having an annular flange extending to a plane below 20 the level of the bottom of said receptacle when said larger bell is in place.

In testimony whereof I have signed my name to this specification.

ROBERTO HEYDRICH y MARTINEZ.
